(57) **CLAIM**

The ornamental design for a tampon insertion device, as shown and described.

DESCRIPTION

FIG. 1 is a bottom orthogonal view of a tampon insertion device according to one embodiment of our new design; FIG. 2 is an upper orthogonal view of the tampon insertion device of FIG. 1;

FIG. 3 is a bottom plan view of the tampon insertion device of FIG. 2;

FIG. 4 is a top plan view of the tampon insertion device of FIG. 2;

FIG. 5 is a right side view of the tampon insertion device of FIG. 2;

FIG. 6 is a left side view of the tampon insertion device of FIG. 2;

FIG. 7 is a proximal end view of the tampon insertion device of FIG. 2; and,

FIG. 8 is a distal end view of the tampon insertion device of FIG. 2.

The broken lines depict portions of the tampon insertion device and form no part of the claimed design.
